SHEET-HANDLING MECHANISM.

Application filed May 12, 1926. Serial No. 108,502.

This invention relates to sheet handling mechanisms and more particularly to sheet or card feeding devices for use in addressing machines, stencil making machines and the like.

The main objects of this invention are to provide an improved feeding mechanism for handling sheets, cards, stencils or the like ⁵ seriatim; to provide a feeding device of this kind which is adapted to handle comparatively thin sheets without jamming or buckling the articles during their travel; to provide a sheet or card feeding mechanism adapted to simultaneously handle articles of various thicknesses; to provide sheet feeding mechanism having improved means for engaging the articles to be fed; to provide a sheet, card or stencil having improved means for engaging a feeding mechanism; to provide an improved form of delivery mechanism for delivering the sheets or other articles to the feeding mechanism; to provide an improved form of ejector for ejecting the cards, one at a time, from the feeding mechanism; and to provide improved positioning means for properly positioning and temporarily holding each sheet stationary in a certain position in its path of travel.

An illustrative embodiment of this invention is shown in the accompanying drawings, wherein:—

Figure 1 is a longitudinal section of a stencil making machine having a feeding mechanism to which this invention is applied, part of the machine being omitted.

Fig. 2 is a similar view, but including part of the driving mechanism.

Fig. 3 is an enlarged vertical section, taken on the line 3—3 of Figure 1 to illustrate the delivery mechanism.

Fig. 4 is a similar view, taken on the line 4—4 of Fig. 1.

Fig. 5 is a plan of the delivery mechanism and card positioning means, part of the magazine being shown in section.

Fig. 6 is a longitudinal section, taken on the line 6—6 of Fig. 5 and showing the positioning means.

Fig. 7 is a longitudinal section, taken on the line 7—7 of Fig. 5.

Fig. 8 is an enlarged transverse section, taken on the line 8—8 of Fig. 1, showing the improved ejector.

Fig. 9 is a front elevation of the ejector.

Fig. 10 is a sectional detail, taken on the line 10—10 of Fig. 1.

Fig. 11 is a perspective of a stencil frame adapted for handling by the improved feeding mechanism.

Fig. 12 is an enlarged section, taken on the line 12—12 of Fig. 1, and showing the improved ejector.

The improved sheet handling mechanism to which this invention is applied is adapted for use in many different types of machines and for handling various kinds of articles but, as herein illustrated, the invention is applied to a stencil making machine. Inasmuch as this invention relates to the sheet handling mechanism, parts of the machine not relating thereto and believed to be unnecessary to a complete understanding of the invention have been omitted from the drawing.

In the specific form herein shown, the improved sheet handling mechanism includes an improved feeding mechanism or conveyer which moves the cards or other sheets seriatim to be operated upon by the various operating mechanisms. The particular conveyer herein illustrated comprises an endless chain having projecting parts adapted to engage apertures in the articles, which are fed thereby along a supporting guideway. The sheets or cards are delivered to the feeding mechanism by an improved delivery mechanism which, in the specific form shown, includes a magazine and means for moving the lowermost card to the plane of the guideway for engagement with the lugs or fingers of the conveyer. An improved ejector is also provided for removing the cards when they reach a certain position on the guideway. In order to properly position each card when it is being acted upon, improved positioning means is also provided for temporarily holding the card stationary.

In the embodiment shown, the improved sheet handling mechanism is applied to a stencil making machine comprising a frame 1 on which is mounted a pair of spaced rails 2 forming a guideway for supporting and guiding stencil frames 3 which are fed through the machine to be operated upon by various mechanisms such as a gluing device 4 and a pneumatic device 5 which applies the tissue patches to the stencil frames.

In the form shown, the improved sheet handling mechanism includes an endless chain conveyer 6, to which the cards or other articles are delivered by an improved delivery mechanism 7 arranged at one end of the machine. Located above the guideway 2, is a positioning device 8 for guiding the cards into proper engagement with the conveyer 6 and for holding them in proper position to be acted upon by the gluing device 4 and the pneumatic device 5. Arranged at the other end of the machine, is an improved ejector 9.

In the specific form shown, the chain conveyer 6 is mounted on a pair of sprockets 10 and 11, which are fixed on horizontal shafts 12 and 13 respectively journaled at opposite ends of the machine. The sprocket shaft 12 is journaled in a bearing 14 which is adjustably mounted on a support 15, so as to be adapted for adjustment both vertically and horizontally for properly positioning the chain. Fixed on the outer end of the shaft 12, is a worm gear 16 meshing with another gear 17 fixed on a shaft 18. The shaft 18 is connected to a continuously driven drive shaft 19 by a Geneva mechanism 20 so as to be intermittently rotated for imparting a step-by-step movement to the conveyer chain. The sprockets 10 and 11 are arranged so as to position the upper running part of the conveyer chain adjacent one side of and parallel to the card guideway 2. Mounted on the chain 6, is a plurality of fingers or lugs 21 which project over the adjacent guide rail for engagement with apertures 22 formed in the card frames, whereby the cards or stencils are fed along the guideway. The lugs 21 and apertures 22 are positioned so as to prevent any lateral shifting of the stencils during their travel along the guideway.

In the form shown, the improved delivery mechanism 7 comprises a magazine or hopper 23 in which a stack of cards or stencils is stored and from which the lowermost card is pushed edgewise by a pusher 24 arranged to move the card onto a pair of cams 25 which lift it into the plane of the guideway 2 for engagement with the fingers 21 of the conveyer.

The pusher slide 24 is located in a guideway 26 below the magazine 23 and is reciprocated by a rocker arm 27 to which it is pivotally connected. The rocker arm 27 is pivotally connected at 28 to the frame 1 and is pivoted at its lower end to a link 29 having a band 30 embracing an eccentric 31 fixed on the drive shaft 19. During the continuous rotation of the shaft 19 and eccentric 31, the arm 27 is rocked back and forth to reciprocate the slide 24 which, upon each forward movement, pushes the lowermost card in the magazine onto the cams 25.

The lifting cams 25 are mounted on shafts 32 arranged below and parallel to the guide

rails 2. Fixed on the shafts 32, are pinions 33 meshing with a gear 34 of a train of gears driven by the drive shaft 19, whereby the cams 25 are continuously rotated. The rotation of the cams 25 is synchronized with the movements of the pusher slide 24 and conveyer chain 6 so that when the pusher moves forwardly, the flat portions of the cams 25 are substantially parallel to the plane of the guideway 2 so as to permit the card or stencil to ride upon the cams. In order to secure the cards against dropping between the cams 25, a pair of brackets 35 is arranged in position to support the ends of the card adjacent its middle portion. The cams 25 rotate in the direction of the arrows, Fig. 4, and lift the card into the plane of the guideway 2 so as to permit the depending conveyer fingers 21 to engage the apertures 22.

In the form shown, the improved positioning device 8 includes a continuously rotatable horizontal shaft 36 journaled in the frame 1 and extending substantially parallel to the guide rails 2 directly above the path of the stencils. The shaft 36 is connected to the drive 19 by the train of gears shown at the right end of Fig. 1. Mounted on the shaft 36, is a series of semi-circular flanges 37 spaced apart a distance slightly greater than the length of the card or stencil being operated upon. The flanges 37 form stops for engaging the forward edges of the cards to accurately position them at certain stages in their travel. One of the stops holds the card in position for engaging the chain conveyer and the other stops position the cards for proper engagement with the gluing device 4 and pneumatic device 5. Also mounted on the shaft 36, are semi-circular cams 38 adapted to engage the rear edges of the cards for urging them forwardly against the stops 37. To prevent injury to the cards or stencils, the cams 38 are cushioned by helical springs 39 embracing the shaft 36, as clearly shown in Fig. 6. The cams 38 are keyed to the shaft 36 so as to permit the yielding action of the cams. The end card, which is being acted upon by the lifting cams 25, is urged forwardly into engagement with the adjacent stop 37 by an upright blade 40 pivotally mounted in the frame 1. The blade 40 is normally urged forwardly by a spring 41 and is arranged to be acted upon by the end of one of the cams 25 for retracting it into position for engaging the next card.

The improved ejector 9 comprises a pair of cams 42 fixed on a shaft 43 journaled in a bracket 44 which is mounted on the frame 1. Fixed on the shaft 43, is a worm gear 45 meshing with another worm gear 46 on a shaft 47 which is geared to the drive shaft 19, whereby the cams 42 are continuously rotated in the direction of the arrows, Fig. 12.

The shaft 43 is located above the path of the stencils and the cams are arranged so as to press downwardly upon the end card or stencil for ejecting it from the guideway. 5 The cams 42 are spaced apart a distance slightly less than the length of a stencil so as to engage the end portions of the stencil frame 3, thereby avoiding injury to the tissue patch. In order to permit the end card 10 to drop from the guideway when pressed downwardly by the cams 42, the outer guide rail 2 is provided with a yielding portion 48 which supports the outer edge of the end card and which is adapted to swing downwardly to release the card under the pressure of the cams 42. The yielding portion 48 is in the form of a stirrup, pivoted to the bracket 44 by a pin 49. The stirrup 48 is normally held in position for supporting the card by means of a spring 50 embracing the pin 49. A suitable receiving hopper or conveyer, not shown, may be placed below the cams 42 for receiving the ejected cards.

In operation, the chain conveyer 6 travels 25 in a step-by-step movement through the action of the intermittently rotating shaft 18. During each brief period of rest of the chain 6, a card is fed from the magazine 23 by the pusher slide 24 which moves it onto the lifting cams 25. The cams 25 are continuously rotated and lift the card into the plane of the guideway 2 for engagement with a pair of lugs 21 on the chain 6. The chain 6 then moves another step to carry the 30 card into the guideway 2. The cards are fed along the guideway to be operated upon by the various mechanisms and, when each card reaches the ejector mechanism, it is forced out of the guideway by the cams 42. 40 With this improved sheet handling mechanism, the articles are fed positively from one station to the next without any possibility of jamming. The apertures 22 serve for handling the stencil frames in the various operations of making stencils and also for handling in the machines in which the stencils are used.

Although but one specific embodiment of this invention has been herein shown and described, it will be understood that numerous details of the construction shown may be altered or omitted without departing from the spirit of this invention as defined by the following claims.

55 I claim:

1. In a device adapted for the flatwise handling of sheets, an endless conveyer having projecting parts adapted to engage apertures in said sheets for feeding them through a predetermined path.

60 2. In a device for handling sheets, a chain conveyer, and lugs on said chain adapted to engage apertures in said sheets for feeding them through a predetermined path.

65 3. In a device of the class described, a

guideway for cards, an endless conveyer, and lugs on said conveyer adapted to engage apertures in said cards for feeding them along said guideway.

4. In a device of the class described, a 70 guideway for sheets, a chain conveyer, and lugs on said chain adapted to engage apertures in said sheets for feeding them along said guideway.

5. In a device of the class described, a 75 horizontal guideway for supporting sheets, an endless conveyer, and lugs on said conveyer adapted to engage apertures in said sheets for feeding them along said guideway.

6. In a device of the class described, the combination with a plurality of stencils having apertures therein, a horizontal guideway for said stencils, an endless conveyer, and lugs on said conveyer adapted to engage the 85 apertures in said stencils for feeding said stencils along said guideway.

7. In a device of the class described, a 90 guideway for sheets, an endless conveyer, and a series of pairs of lugs on said conveyer adapted to engage pairs of apertures in said sheets for feeding said sheets along said guideway.

8. In a device of the class described, a 95 guideway for sheets, an endless conveyer located at one side of said guideway, and lugs on said conveyer projecting transversely across said guideway for engagement with apertures in said sheets.

9. The combination with an addressing 100 machine having an endless conveyer provided with projecting portions, of an address stencil comprising a stencil sheet, and a rectangular frame forming a border for said sheet and having an aperture therein for receiving one of said projecting portions.

10. The combination with an addressing machine having an endless conveyer provided with projecting portions, of an address stencil comprising a stencil sheet, and a rectangular frame forming a border for said sheet and having a pair of apertures spaced apart longitudinally of said frame for receiving two of said projecting portions, said apertures being elongated and being inclined with respect to the longitudinal axis of said stencil.

11. In a device of the class described, a 115 magazine for sheets, feeding mechanism for said sheets, and delivery means arranged to deliver the lowermost sheet in said magazine to a position below said feeding mechanism and to elevate it into another position for engagement with said mechanism.

12. In a device of the class described, a 120 magazine for supporting a stack of cards, mechanism for feeding said cards seriatim, means for moving the lowermost card of the stack from said magazine to a position below said feeding mechanism, and other 125

80

95

100

105

110

115

120

125

130

means for elevating the card to another position for engagement with said mechanism.

13. In a device of the class described, a magazine for supporting a stack of cards, mechanism for feeding said cards seriatim, a pusher for moving the lowermost card of the stack from said magazine to a position below said feeding mechanism, and means for elevating the card to another position for engagement with said mechanism.

14. In a device of the class described, a magazine for supporting a stack of cards, mechanism for feeding said cards seriatim, a pusher for moving the lowermost card of the stack from said magazine to a position below said feeding mechanism, and a cam arranged to lift the card into position to engage said mechanism.

15. In a device of the class described, a magazine for supporting a stack of cards, mechanism for feeding said cards seriatim, a pair of cams arranged below said feeding mechanism, a pusher for moving the lowermost card of the stack from said magazine onto said cams, and means for actuating said cams to lift the card into position to engage said feeding mechanism.

16. In a machine of the class described, a track, a chain moving in parallel relation with said track, said chain having lugs projecting across the plane of the track, means for feeding cards under the chain, and other means for moving the cards into engagement with the lugs and into the supporting plane of said track.

17. In a machine of the class described, a track, a chain moving in parallel relation with said track, said chain having lugs projecting across the plane of the track, means for feeding cards transversely under the chain, and other means for moving the cards into engagement with said lugs and into the supporting plane of said tracks.

18. In a machine of the class described, a support forming a guideway, a chain moving along said support, said chain having

lugs projecting downwardly across the plane of said support, means for feeding cards into engagement with said lugs, and other means for guiding the cards onto the support.

19. In a machine of the class described, a horizontal support forming a guideway, a chain moving along the support, said chain having lugs projecting downwardly across the plane of said support, means for feeding cards under the chain, and other means for lifting the cards into engagement with said lugs and into the plane of said support.

20. In a machine of the class described, spaced supports, a chain moving alongside the supports, said chain having lugs extending over and between the supports, means for feeding cards under the chain adjacent the end of the supports, and other means for lifting and guiding the cards into engagement with said lugs and onto the support.

21. In a machine of the class described, a conveyer chain having downwardly projecting lugs, means for feeding cards transversely under the chain and into engagement with said lugs, and a track for holding the cards in said engagement.

22. In a machine of the class described, a track, a moving chain at one side of said track, lugs on said chain projecting over and downwardly into the plane of the track, and means for delivering cards onto said track.

23. In a machine of the class described, a track, a chain moving alongside said track, said chain having lugs overhanging and projecting into the track, rotating shafts mounted at the end of and below the plane of said track, said shafts having lobular cams for raising cards into the plane of the track to engage said lugs, and means for feeding the cards onto said cams.

Signed at Chicago this 6th day of May, 1926.

PAUL A. GOLNICK.
